UNITED STATES PATENT OFFICE.

CLAUD CALLISON, OF LOYAL, OKLAHOMA.

MILK BOX.

Application filed September 6, 1924. Serial No. 736,812.

The invention provides for the safe delivery of milk and other articles usually delivered to families at an early hour before the usual time for rising, the box being 5 weather-proof and of a durable structure and supplied with an automatic lock to which the one making the delivery or the tradesman has a key, the cover of the box being attached to the latter by spring hinges 10 whereby when the lock is sprung the cover automatically opens thereby enabling the merchandise, milk or the like to be conveniently removed from or placed within the box, the cover when closed automatically 15 locking.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without 25 departing from the nature of the invention.

Referring to the accompanying drawings forming a part of the specification.

Figure 1 is a front view of a milk box embodying the invention,

Figure 2 is a sectional view on the line 2—2 of Figure 1,

Figure 3 is a sectional view on the line 3—3 of Figure 2,

Figure 4 is a vertical transverse sectional view on the line 4—4 of Figure 3,

Figure 5 is an enlarged detail view of a part of the locking mechanism, and

Figure 6 is a detail sectional view on the line 6—6 of Figure 5.

Corresponding and like parts are referred to in the following description and designated in the several views of the drawings by like reference characters.

The box may be of any preferred construction and as shown comprises a body 10 preferably of sheet metal and a plurality of rods 11 grouped about the exterior of the box to form protective means therefor. A cover 12 closes the top of the box and is connected thereto by means of spring hinges 13 which may be of any type and which normally hold the cover in open position when the lock is sprung so that merchandise may be conveniently placed within the box or removed therefrom.

A keeper 14 is located upon the back of

the box and a lock member 15 is slidable therein and is connected by means of a brace 16 to the cover 12 with the result that the cover and lock member move together. A 60 latch 17 is mounted in the keeper 14 and is adapted to engage a notch in a side of the lock member 15 to secure the latter when the cover 12 is closed. A bar 18 disposed horizontally carries the latch 17 and is normally moved in one direction by means of the spring 19 which is mounted upon a reduced portion 20 of the bar and which is confined between elements 21 and 22, the latter being attached to the outer end of the reduced part 20 and the element 21 being let into an opening in a door jamb 23 or like part and to which is fitted an escutcheon 24. The element 22 may be pressed upon to release the lock or the latter may be sprung by means of either one of the keys 24 or 25, the latter being insertable in a key-hole 26 in the front of the box and the key 24 being fitted to the part 23 as indicated most clearly in Figures 5 and 6.

While the box is designed primarily for receiving milk bottles or jars, it is to be understood that it may be utilized for the safe delivery of bread or other merchandise which is usually delivered at a time when the members of a household are not up and about, thereby insuring the safe delivery and preventing the usual pilfering which is both annoying and expensive.

The key 24 is preferably fixed and may be of any desired construction and arrangement. The tradesman's key 25 may be of any design and, as shown, is insertable in a guide 25^a attached to the inner side of the front of the box and extending inwardly and 95 terminating adjacent the keeper 14. The key is preferably of sectional formation, a section 25^b remaining within the guide 25^a and the outer section or part being retained by the tradesman.

What is claimed is:

1. A device of the class described comprising a box, a closure therefor, a lock member connected with said closure, a lock bar 105 slidably associated with the box, a latch on said bar, a keeper within the box having a slot in which said latch is movable, said latch being associated with said lock member, a tube extending from the keeper to the remote wall of the box to constitute a guide, and 110 a key operable in said tube having a bit coacting with said latch.

2. A lock box, comprising a box, a cover therefor, spring means normally urging the cover to open position, a lock member, a brace connecting said lock member and the
5 cover, a bar slidably associated with the box, a latch carried by said bar and engageable with a notch in the lock member to hold it

in locked position, means yieldingly holding the latch in engagement in the notch, and
10 means engaging the bar to actuate it to unlocked position.

In testimony whereof I affix my signature.

CLAUD CALLISON.
